UNITED STATES PATENT OFFICE.

JOHN C. HENDERSON, OF WASHINGTON, DISTRICT OF COLUMBIA.

MANUFACTURE OF DRAW-PLATES OR DIES.

1,243,167.

Specification of Letters Patent. Patented Oct. 16, 1917.

Application filed June 5, 1917. Serial No. 172,963.

To all whom it may concern:

Be it known that I, JOHN C. HENDERSON, a citizen of the United States, residing in the city of Washington, District of Columbia, have invented new and useful Improvements in the Manufacture of Draw-Plates or Dies, of which the following is a specification.

- My invention relates to the manufacture 10 of dies or die plates for drawing wire and the like; and it consists in casting molten metal by compression in a permanent metal mold, which mold may be chilled by the agency of an external medium such as water 15 or air that is caused to pass through conduits in the molding members for the express purpose of rapidly extracting heat from the mold and the molten metal under pressure, so as to give it a "set," although 20 the metal mold itself may be relied upon to do this without the assistance of some external heat extracting source. After the 25 mold or formed die or draw plate has received its "set," it is still further chilled by being rapidly immersed in a liquid bath of water or other chilling fluid to fix the homogeneity of the structure and the changed molecular condition of the metal of the die or plate in passing from a molten state to 30 a solid homogeneous structure, whereby there is produced a metal die or plate having all of the characteristics of hardened tool steel.

The particular object of my invention is 35 to chill every portion of the blank forming the die or draw plate throughout the whole of the mass cast. I have found by experiment that this chilling can not be removed even when the chilled die or draw plate is 40 brought to a red heat during working conditions.

Prior structures of this class only have had the outer surface chilled, that is, the skin. Accordingly when this chilled skin 45 was removed by perforating the blank to form the eye of the die or draw plate the metal was comparatively soft, hence the whole object of chilling was defeated, and the article rendered useless for the purpose 50 for which it was manufactured.

With my invention the chilled pressure cast homogeneous die blank can only be perforated in a satisfactory manner to form the eye of the die or draw plate for wire 55 drawing purposes by the use of a steel point and diamond dust aided by the use of a lu-

bricant as diamond dies are drilled at the present. And further, I produce an article of manufacture that answers the purposes of the well known dies or draw plates made 60 at the present time by the use of precious stones, and hardened steels and their alloys, which device is exceedingly cheap to manufacture and gives very satisfactory production or manufacturing results.

My present invention will be more fully understood from the accompanying drawing illustrating the means of producing the die or draw plate blank.

Figure 1 is a view of the male and female 70 mold in partial section containing a batch of metal to be pressure cast.

Fig. 2 is a perspective view of the die or draw plate blank before it is perforated.

Fig. 3 is a partial vertical section of the 75 die or draw plate showing the eye or perforation therein.

Referring now to the drawing, 1 is a female member of a metal mold of large mass having an opening 2 for the reception 80 of the plastic metal 3, and 4 is a plunger for pressing the metal into the opening 2 of the member 1 to form a blank to be used as a die or draw plate. The object of making the member 1 of large mass is to effect chilling, although some external medium may 85 also be used for this purpose.

In Fig. 2 the formed and chilled blank 3^a is illustrated after it has been properly 90 formed and treated, while in Fig. 3 the blank 3^a is shown with a perforation or eye 5. This is the condition of the die when ready for use in the drawing of wire.

In the production of a blank for a wire drawing die or draw plate, I commence by 95 placing a batch of molten metal 3 in the opening 2 of the mold 1 and then press it into shape by the plunger 4 by the aid of hydraulic or other pressure. The mass of the female mold member chills the blank 100 and gives it the set which changes the properties of the metal cast, in other words, the chemical constituency of the cast iron is changed so that it has properties similar to hardened steel. If the first chilling is 105 deemed insufficient, a further chilling is caused by immersing in a fluid bath or other external means. After this procedure is gone through the die or draw plate is perforated.

In accordance with the provisions of the patent statutes, I have described the prin-

ple of operation of my invention, together with the article which I now consider to represent the best embodiment thereof; but I desire to have it understood that the article shown is merely illustrative, and that the invention can be carried out by other equivalent means contemplated within the scope of the claims.

Having thus described my invention I claim:

1. As a new article of manufacture, a cast draw plate blank of compressed iron chilled throughout its entire mass under pressure.
2. As a new article of manufacture, a pressure cast draw plate blank of compressed iron chilled throughout its entire mass by chilling during and after casting.

3. As a new article of manufacture, a molded draw plate or die blank of compressed iron chilled throughout the whole of its molecular structure. 20

4. As a new article of manufacture, a molded draw plate or die blank of compressed iron double chilled throughout the whole of its molecular structure. 25

5. As a new article of manufacture, a molded draw plate or die blank of compressed iron having the constituency of cast iron and the properties of hardened steel. 30

6. As a new article of manufacture, a molded draw plate or die blank of compressed iron having the chemical constituency of cast iron and the physical properties of hardened steel.

JOHN C. HENDERSON.
